UNITED STATES PATENT OFFICE

2,386,154

PROPELLER

Max. Weber, Chicago, Ill.

Application November 6, 1942, Serial No. 464,813

1. Claim. (Cl. 170—159)

This invention relates to air screws or propellers.

An object of this invention is to provide a propeller structure which is so constructed as to provide a substantially floating structure wherein end thrust is substantially eliminated.

Another object of this invention is to provide a propeller structure in which the tip portion of each blade is provided with a pitch reverse to the pitch on the remaining portion of the blade, the reverse pitch effecting to eliminate end thrust caused by the remaining portion of the blade, and also enlarging the suction zone for the blades.

A further object of this invention is to provide a propeller structure in which the central portion thereof is formed of a length equal to substantially one-half the length of each blade, the central portion being pitched to the terminal end thereof and providing an axial spiral cyclonic air stream.

A further object of this invention is to provide a propeller structure which is so constructed as to reduce the noise normally formed by propellers now in use.

A further object of this invention is to provide a propeller structure which will permit greatly increased propeller speeds without causing fatigue in the tip portions of the blades, as is now the case with propellers at present available.

A further object of this invention is to provide a propeller structure in which the suction caused by partial vacuum on the rear sides of the blades, is counterbalanced by the forward thrust effected by reversing the pitch at the tip ends of the blades, the effect of the reversed pitch on the outer ends being to provide for inward movement of the air radially of the propeller structure instead of coaxially as is at present the case with propellers now in use.

A further object of this invention is to provide a propeller structure including a main or inner driving zone, a neutral intermediate zone, and an outer or rearward driving zone, the latter zone being of such width as to counterbalance the thrust of the main zone and effect a substantial floating of the propeller.

A further object of this invention is to provide a propeller structure in which the air circulating efficiency thereof is increased without increase in power or size of the structure.

To the foregoing objects and to others which may hereinafter appear, the invention consists of the novel construction, combination, and arrangement of parts, as will be more specifically

referred to, and illustrated in the accompanying drawings, wherein an embodiment of the invention is shown, but it is to be understood that changes, variations and modifications may be resorted to which fall within the scope of the invention as claimed.

In the drawings:

Figure 1 is a detail front elevation of a propeller constructed according to an embodiment of this invention;

Figure 2 is a plan view of the propeller;

Figure 3 is a detail side elevation of one of the propeller blades;

Figure 4 is a sectional view taken on the line 15 4—4 of Figure 3;

Figure 5 is a sectional view taken on the line 5—5 of Figure 3;

Figure 6 is a sectional view taken on the line 6—6 of Figure 3;

Figure 7 is a sectional view taken on the line 7—7 of Figure 3;

Figure 8 is a sectional view taken on the line 8—8 of Figure 3;

Figure 9 is a sectional view taken on the line 9—9 of Figure 3;

Figure 10 is a sectional view taken on the line 10—10 of Figure 3;

Figure 11 is a sectional view taken on the line 11—11 of Figure 3;

Figure 12 is a sectional view taken on the line 12—12 of Figure 3;

Figure 13 is a diagrammatic view showing the air currents generated by this propeller, and the movement of air caused by the generated air currents; and

Figure 14 is an end elevation of the air currents showing the movement thereof caused by this propeller.

Referring to the drawings, the numeral 15 designates generally a hub structure and the numeral 16 designates one of a series of blades carried by or formed integral with the hub structure 15. The hub structure 15 is adapted to be secured in any suitable manner to a power shaft, such as a fanmotor shaft, to effect rotation of the propeller at the desired speed.

The hub structure 15 has projecting forwardly therefrom, a plurality of radially arranged blades 17, which have a relatively deep pitch and the blades 17 terminate in an apex or axially disposed point 18 which is coaxial with the axis of the hub 15. The blades 17 being disposed on a relatively deep pitch, are adapted, as shown in Figure 13, to produce a centrally disposed spirally rotating column of air indicated by the arrows 19

in Figure 13. This central, spirally rotating column of air 19 is adapted to move forwardly at a greater speed than the speed of movement of the air caused by the blades 16, as will be hereinafter described.

The blades 16, at their inner ends 20, merge with the outer ends of the hub blades 17, and the pitch of the inner end portions 20 of the blades 16 gradually reduce in pitch thereof toward the outer ends of the blades 16. The blades 16 have a straight leading edge 21 and a longitudinally curved following edge 22. The forward or thrust sides 23 of the blades 16 are substantially flat whereas the rear or trailing sides 24 of the blades 16 are curved, as shown in Figures 5 to 12 inclusive. The pitch of the blades 16 gradually reduces toward the outer ends of these blades, in such a manner that the thrust of the forward sides 23 of the blades will be substantially equalized from the root or inner portion 20 thereof to a point designated by the line 25. The line 25 indicates, as shown in Figure 6, a neutral zone wherein the pitch of each blade 16 is zero, or in other words the front face 23 of each blade 26, at the point 25, is parallel with the plane of rotation of the blades 16. The blades 16, outwardly from the neutral zone 25, is formed with a reverse pitch, as shown in Figures 4 and 5. The reversely pitched zone 26 is relatively shallow and constitutes a means for counter-balancing the thrust of the blade effected by the inner zone 27. This reverse pitch 26 eliminates in great part the endwise thrust on the hub 15 so as to cause a substantially floating of the blade 16 within the plane of rotation.

The reverse pitch also provides a means whereby the air or fluid, outwardly from the outer circle of the blades 16, is drawn inwardly, as shown by the arrows 28 in Figure 13. In other words, the reversely pitched zone or portion 26 causes the air or fluid stream to move radially inwardly of the blades 16 from the outer ends thereof in addition to stabilizing or counter-balancing the endwise thrust on the propeller blades. The length of the reversely pitched portion 26 is substantially one-fourth the radius of each blade 16, and provides a means for eliminating the objectionable hum or sound normally produced by high speed propeller blades at the tips thereof. Reverse pitching of the blades by eliminating the thrust on the forward sides thereof also provides a means whereby the fatigue caused at the tips of the blades is substantially reduced, if not entirely eliminated, when the propeller is operated at a very high speed.

The hub blades 17 are of a length substantially equal to one-half the radius of each blade 16 and these blades 17 provide a means whereby the centrally disposed vacuum normally produced by propeller blades, is eliminated.

The combination of the centrally disposed hub blades 17, and the reversely pitched blades or portions 26 of each propeller blade 16, provides a propeller blade structure which is more efficient in operation than propeller blades at present available.

Referring now to Figures 13 and 14 the hub blades 17 produce the central spiral column of air or fluid 19 which travels at a relatively high speed and also produce the spiral column of air 29 which is produced by the outer portions of the blades 17 where they merge with the inner or root portions 20 of the blades 16. The blades 16 produce a spiral column of air, indicated by the arrows 30 in Figure 13, this column of air moving at a slower speed than the column of air or fluid 29 or the column of air or fluid 19. The air enters between the blades 16 from the rear sides thereof, as shown by the arrows 31, and also enters, as shown by the arrows 28, from the outer ends of the blades, the latter mentioned air or fluid moving radially inwardly along the sides of the blades 16. This blade structure has been tested under a fluoroscope with smoke or colored vapor, and the spiral movements of the air, as shown in Figures 13 and 14, have been clearly discerned under these tests.

The inner stream or column of air or fluid 29, and also the central column or stream of air or fluid 19, appears to expand, as indicated at 32, at a point some distance forwardly from the blades and substantial portions of the air or fluid streams continue forwardly in an expanded condition, as shown at 33, until the air streams strike an abutment or wall facing the propeller blades.

The propeller structure, as herein shown, embodies five blades but it will, of course, be understood that the propeller structure may have any desired number of blades depending in great part upon the speed of the blades and the force of air or fluid which is to be generated by the blades. The provision of the forwardly projecting central or hub blades 17 produce what may be termed a cyclonic effect due to the high speed of movement of the central air or fluid column 19. This cyclonic action causes a greater movement of air within the several air streams as the outer air streams tend to be drawn inwardly as they move forwardly. The propeller structure herein disclosed is an improvement over the propeller structure embodied in my prior Patent No. 1,933,948, issued November 7, 1933.

I claim:

A propeller comprising a hub, and a plurality of blades carried by said hub, said blades at their inner ends extending forwardly of said hub and terminating at substantially the axial center of said hub, the pitch of each blade gradually decreasing from the hub axis toward the outer end thereof, each blade comprising a forwardly pitched forward thrust area for the major length thereof, a reversely pitched tip area and an intermediate neutral area defining a neutral zone between the forward thrust area and the reversely pitched tip area, the pitch of said tip being substantially less than the average forward pitch of the blade whereby to provide a substantially balanced thrust.

MAX WEBER.
